UNITED STATES PATENT OFFICE.

GILLES HOLST, WILLEM OTTO JULIUS, AND EKKO OOSTERHUIS, OF EINDHOVEN, NETHERLANDS, ASSIGNEES TO NAAMLOOZE VENNOOTSCHAP PHILIPS' GLOEILAMPENFABRIEKEN, OF EINDHOVEN, NETHERLANDS.

GLOW CATHODE RECTIFIER.

Application filed July 28, 1923, Serial No. 654,482, and in the Netherlands July 31, 1922.

The present invention relates to devices with one or more glow-cathode-rectifiers and has for its object to increase the life of the said rectifier-tubes by a particular combination or connection of the devices.

As a rule the life of glowcathode-rectifiers depends on that of the cathode for which a tungsten coil is frequently used. Consequently an increase of the life of the cathode 10 constitutes at the same time a lengthening of the life of the tube.

Applicants have found that the relatively short life of the cathode is partly due to an unequal charge on the incandescent wire. 15 This unequal charge occurs during that part of the period of the feeding alternating current during which the current rectifier passes through. In this lapse of time both the heating current and the current rectified (discharge current) flow through the incandescent wire.

In every point of the incandescent wire, the current flowing at a given moment is 20 equal to the algebraic sum of the heating current and the discharge current. The former is equal for all points of the incandescent wire but the latter varies from point to point. If therefore the current is rectified, the strength of the current in the wire is 25 different for different points of same. The actions of the current in a given point of the wire from moment to moment accumulate to a resulting effect manifesting itself by a certain heating, disintegration or more 30 generally wear of the wire (in the said point) which might be caused quite as well by an imaginary effective current not varying with the time.

According to the invention it is possible 35 by a correct choice of the temporary course of the heating current relative to the discharge-current to make the effective values of the currents in the different points of the wire less unequal. As the heating current 40 is usually a normal alternating current, it may be also said that according to the invention the inequality of the effective currents from point to point in the wire is decreased 45 by a correct regulation or choice of the phase of the heating current relative to the temporary course of the discharge-current.

It has further been recognized that in 50 many tubes the phase of the heating current

can be relatively accurately indicated beforehand. If the discharge-current is imagined to be decomposed into a continuous current and several alternating currents the frequencies of which are harmonics of the heating current frequency, there must be 55 according to the invention a phase difference of substantially 90° between the heating current and the first harmonic of the discharge-current. The first harmonic of the discharge current is considered to be that alternating current component of the discharge current, 60 which has the same frequency as the heating current.

When applying the principle of the invention to an arrangement connected to a three-phase system, the object of the invention can be realized by a simple connection. The device is preferably provided 70 with a set of star-connected anode-windings and a set of star-connected windings supplying current to the glowcathodes, the two star-points being connected together with the interposition of a battery or other consumption apparatus, the anodes being connected to the free ends of the anode-windings and the glowcathodes to the free ends of the windings supplying current to the glowcathodes in such a manner that the incandescent wire of each tube is connected to those windings the voltages of which are displaced in phase 120° and 240° respectively 80 in relation to the voltages of the anode-windings to which the anodes are connected.

The accompanying drawings represent a particular embodiment of the invention applied to a three-phase system. In the said drawings Figure 1 is a diagram of an arrangement according to the invention, whereas Figure 2 shows more fully the connection of the various apparatus.

In Figure 1 t_1 , t_2 and t_3 are the secondary windings of a transformer and t'_1 , t'_2 and t'_3 are the secondary windings of another transformer. g_1 , g_2 and g_3 refer to the three incandescent wires of three rectifying tubes the anodes of which are indicated by a_1 , a_2 and a_3 . a_1 and g_1 belong to the same tube, likewise a_2 and g_2 and also a_3 and g_3 . The windings t_1 , etc., t'_1 , etc., and g_1 , etc., 100 are as regards their direction illustrated as 105 vectors.

As shown in the drawing, the two sets of

windings t_1 , etc., and t'_1 , etc., are star-connected and the two star-points are connected together with the interposition of a battery e .

The anode a_1 is connected to the free end 5 of the winding t_1 and the corresponding incandescent wire g_1 is connected to the free ends of the windings t'_2 and t'_3 .

g_1 considered as a vector is perpendicular 10 to t_1 and the incandescent current through g_1 is consequently displaced relatively to the voltage of the winding t_1 .

As the first harmonic of the discharge-current can be considered to be in phase with the voltage of the winding t_1 it is 15 apparent that the connection illustrated comes up to the requirements of the present invention.

Figure 2 shows more fully a device 20 according to the principle on which the device shown in Figure 1 is based.

The primary windings 1, 2 and 3 of a transformer are delta-connected whereas the 25 two sets of secondary windings 4, 5, 6, and 7, 8, 9 are star-connected. The regulable windings 4, 5 and 6 are connected to the anodes of the tubes 10, 11 and 12, whereas the incandescent-current windings 7, 8 and 30 9 are connected to the incandescent wires in accordance with the principle on which the device shown in Figure 1 is based.

The two star-points are connected together with the interposition of the battery 35 to be charged, a regulating resistance 14 and an ammeter 13 for reading the continuous current.

It will be obvious to those skilled in the art that the broad principle of the invention may be applied in many other ways than herein described and illustrated.

What we claim is:—

1. In a rectifying system, a glow cathode rectifier, an alternating current supply for the cathode of said rectifier and an alternating current supply for the discharge within said rectifier, the said two supplies being 45 substantially 90 degrees out of phase.

2. In a rectifying system, comprising glow cathode rectifiers, three glow cathode rectifiers each comprising an anode and a glow cathode, at least one three phase trans-

former, said transformer being provided with a set of star-connected anode windings and a set of star-connected cathode windings for supplying current to the glow cathodes, said cathode windings normally 55 having electromotive forces displaced 120° and 240° respectively in relation to the electromotive forces of the anode windings, a consumption apparatus, the star points of said windings being connected together 60 through said consumption apparatus, the anodes of said rectifiers being connected to the free ends of said anode windings and said glow-cathodes being connected to the free ends of the windings supplying current thereto in such a manner that in each of said rectifiers the glow-cathode of a particular rectifier is connected to those windings the electromotive forces of which are displaced 120° and 240° respectively in relation 70 to the electromotive force of the anode winding to which the anode of the same rectifier is connected.

In testimony whereof we affix our signatures:

GILLES HOLST.
WILLEM OTTO JULIUS.
EKKO OOSTERHUIS.
